Specification for Design.

Patented Dec. 20, 1921.

Application filed November 15, 1920. Serial No. 424,302. Term of patent 3½ years.

To all whom it may concern:

Be it known that I, CHARLES H. FORBELL, a citizen of the United States, residing at Douglas Manor, in the county of Queens and State of New York, have invented a new, original, and ornamental Design for an Advertising Novelty, of which the following is a specification, reference being had to the accompanying drawings, forming a part thereof.

The drawing is a face view of an advertising novelty made in accordance with this design.

I claim:

The ornamental design for an advertising novelty as shown.

In testimony whereof, I have hereunto set my hand, this 26th day of October, 1920.

CHAS. H. FORBELL.
